Attorneys.

UNITED STATES PATENT OFFICE.

CHARLES H. WILSON, OF MINNEAPOLIS, MINNESOTA, ASSIGNOR OF ONE-HALF TO EDMUND BURKE, OF MINNEAPOLIS, MINNESOTA.

HEATER FOR WATER-CIRCULATING SYSTEMS OF INTERNAL-COMBUSTION ENGINES.

Application filed February 18, 1925. Serial No. 9,963.

To all whom it may concern:

Be it known that CHARLES H. WILSON, a citizen of the United States, residing at Minneapolis, in the county of Hennepin and 5 State of Minnesota, has invented certain new and useful Improvements in Heaters for Water-Circulating Systems of Internal-Combustion Engines, of which the following is a specification.

10 My invention relates to heaters for water-circulating systems of internal combustion engines. An object is to provide an electric heater which is located in the water-circulating system of the engine so that when the 15 motor vehicle is standing in the garage in cold weather, current may be readily supplied to the heater for the purpose of preventing the water from freezing or becoming chilled to such an extent that starting 20 is difficult. Another object of the invention is to provide a process of manufacturing the heater in economical and expeditious manner not requiring the casting of metal parts.

25 The full objects and advantages of my invention will appear in connection with the detailed description thereof, and the novel features embodied in my inventive idea will be particularly pointed out in the claims.

30 In the accompanying drawings which illustrate the application of my invention, Fig. 1 is an elevational view showing the device applied to the water-circulating system of an internal combustion engine. Fig.

35 2 is a sectional view of the heating element before it has been coiled up. Fig. 3 is a sectional view showing the heating element in coiled condition within a section of rubber hose.

40 Referring to the construction shown in the drawings, an internal combustion engine 10 is indicated in Fig. 1 having a cylinder jacket inlet connection 12 and a radiator outlet connection 14 leading from the bottom of

45 the radiator 16. The connecting members 12 and 14 are joined by a section of rubber hose 18 having reduced ends 20 and 22 which fit respectively over the members 12 and 14 and are secured thereto by clamps 24 and 26.

50 Within the hose section 18 is a heating element preferably placed therein by molding the hose around the heating element which is made up as follows:

A coiled resistance wire 28 has insulated

end portions shown at 30 and 32 which pass through cylinders 34 and 36 of mica or other insulating material. A sheath 38 of asbestos or other insulating material covers the coiled wire 28 and the mica cylinders. This portion of the device is placed inside of a metallic tube 40, preferably of copper which is provided with corrugations 42 and 44 at its respective ends. The tube 40 is then coiled up on a mandrel into the form shown in Fig. 3 and the rubber hose 18 is molded around the coil in such manner that the corrugations 42 and 44 are anchored in the wall of the hose. The wall of the hose at these two places is preferably thickened by bosses 46 and 48. The insulated ends 30 and 32 of the resistance wire are extended and connected with a plug 50 which is adapted to be turned into an electric light socket.

The operation and advantages of my invention will be understood in connection with the foregoing description. When the motor vehicle is placed in a garage or even when standing outside, attachment is readily made to an electric light socket or to any convenient source of electrical energy. Current passing through the resistance coil 28 heats the same and also the metallic tube 40, the latter presenting a large area of heating surface to the water which is thereby heated to such an extent as to cause it to circulate and prevent freezing or undue chilling in any part of the circulating system. It is apparent that the heated water will rise and circulation will be caused in the same direction in which the water circulates when the engine is running. The heater may be conveniently and economically manufactured by my process without the necessity of casting any metallic parts.

I claim—

1. A heater for water circulating systems of internal combustion engines comprising a section of hose adapted for attachment in a pipe of the circulating system, a coiled metallic tube in said hose having its ends extending through the wall thereof, insulating material within said tube, and a coiled resistance wire within said insulating material having its ends extending out of the ends of said tube for connection with a source of electrical energy.

2. A heater for water circulating systems of internal combustion engines comprising

a section of hose adapted for attachment in a pipe of the circulating system, a coiled metallic tube in said hose, having its ends extending through the wall thereof, cylinders of insulating material in the ends of said tube, a sheath of insulating material within said tube, and a coiled resistance wire within said sheath having its ends extending out of said cylinders for connection 10 with a source of electrical energy.

3. The process of manufacturing electric heaters which consists of placing a coiled resistance wire in a metallic tube with said wire surrounded by insulating material, forming said tube together with the enclosed wire into a coil, and molding a rubber hose around said coil with the ends of 15

the coil extending through the wall of the hose.

4. The process of manufacturing electric 20 heaters which consists in placing cylinders of insulating material in the ends of a metallic tube, placing a coiled resistance wire in said tube with the wire surrounded by insulating material and having its ends extending through said cylinders, forming said tube together with the enclosed wire 25 into a coil, and molding a rubber hose around said coil with the ends of the coil extending through the wall of the hose.

In testimony whereof I have hereunto affixed my signature.

CHARLES H. WILSON.
